UNITED STATES PATENT OFFICE.

BENJAMIN V. KERSHNER, OF KANSAS CITY, MISSOURI, ASSIGNOR TO UNION SPECIAL MACHINE COMPANY, OF CHICAGO, ILLINOIS, A CORPORATION OF ILLINOIS.

SEWING MACHINE FOR STITCHING WAISTBANDS.

Application filed March 30, 1920. Serial No. 369,865.

To all whom it may concern:

Be it known that I, BENJAMIN V. KERSHNER, a citizen of the United States, residing at Kansas City, in the county of Jackson, 5 State of Missouri, have invented certain new and useful Improvements in Sewing Machines for Stitching Waistbands, of which the following is a description, reference being had to the accompanying drawing and 10 to the figures of reference marked thereon.

The invention relates to new and useful improvements in sewing machines, and more particularly to a sewing machine for forming waist bands for trousers.

15 An object of the invention is to provide a sewing machine with guiding devices constructed and so related to each other and to the stitching mechanism as to guide and direct to the stitching mechanism a facing strip with its edges inturned, a body garment, a stiffening strip, a binding for the stiffening strip and a tacking strip.

In the drawings:—

Figure 1 is a front view of a portion of a 25 sewing machine having my improved guiding devices attached thereto;

Fig. 2 is a view of the same parts from the end of the machine;

Fig. 3 is a plan view of a portion of the 30 work support and guiding devices with the lining strip guide removed;

Fig. 4 is a transverse sectional view through the guiding devices on the line 4—4 of Fig. 3;

35 Fig. 5 is a view of the tacking guide and showing its relation to the work support;

Fig. 6 is a transverse sectional view through the guiding device for the lining strip;

40 Fig. 7 is a view, showing more or less diagrammatically the needle and loopers of the stitching mechanism;

Fig. 8 is a sectional view through the parts stitched on the machine.

45 In carrying out the invention, I have applied my guiding devices to a sewing machine having two spaced needles and a looper cooperating with each needle so as to form two independent lines of stitching. Attached to 50 the overhanging arm of the machine is a guiding device for the lining strip of the waist band, which guiding device inturns both the upper and lower edges of said lining. Beneath this guiding device is a guiding 55 device for the stiffening strip, and

mounted on the guiding device for the stiffening strip is an edge guide so disposed as to direct the body fabric between the edge of the stiffening strip and the infolded edge of the lining strip. Associated with the 60 guiding device for the stiffening strip is a binding guide for directing the binding so as to fold the same about the edge of the stiffening strip, and directly beneath the guiding device for the stiffening strip is a guiding 65 device for a tacking strip. The parts are associated so that one edge of the stiffening strip and one edge of the lining strip will be stitched by one line of stitching to the upper edge of the body fabric, while the other in- 70 folded edge of the lining strip, the binding for the stiffening strip, the stiffening strip and the tacking strip will be stitched together by the other line of stitching.

Referring more in detail to the drawings, 75 the invention is shown as embodied in a sewing machine having a work support 1 and an overhanging arm 2, in which a needle bar 3 reciprocates, carrying two needles 4 and 5. Cooperating with the needle 4 beneath the 80 work support is a looper 6, and cooperating with the needle 5 is a looper 7. The needles are widely spaced, as shown in the drawings, and each needle and its associated looper forms a line of stitching, so that two independent spaced lines of stitching are formed. 85

Referring briefly to Fig. 8, it will be noted that the waist band construction consists of a lining strip L, which is infolded, as indicated at l, and this infolded edge lies against the 90 face of the body fabric, indicated at B. A stiffening strip, indicated at S, is placed beneath the body fabric, and a line of stitching indicated at N, unites the infolded edge of the lining strip, the body fabric and the edge 95 of the stiffening strip. At the same time that this line of stitching is being formed, a separate line of stitching N' is formed, which passes through the other infolded edge of the lining strip, indicated at l'. Extending about the edge of the stiffening strip is a binding, indicated at C, and beneath the binding is a tacking strip T, and this line of stitching N', which passes through the infolded edge of the lining strip, also passes 100 through the binding C, the stiffening strip, and the tacking strip T.

The lining strip is led through a lining strip guide indicated at 8 in the drawings. This lining strip guide 8 is carried by a 110

- bracket arm 9 which is pivoted to the overhanging arm of the machine so that it may be raised and lowered to give access to the needles for threading. The lining strip 5 guide 8 is of the usual construction and is so formed as to inturn the edges of the lining strip as indicated at *l* and *l'*. The construction of this lining strip guide will be clear from the drawings, and particularly Fig. 10 6 thereof, which is a cross sectional view through this guide. It will be noted that the guide is formed with recesses 10 and 11, which infold the respective edges *l* and *l'* of the lining strip.
- 15 Directly beneath the lining strip guide are guiding devices for the stiffening strip, the binding, the tacking strip and the body fabric. These guiding devices are all mounted upon the bracket arm 11^a which is 20 secured to the work support by screws 12 and 13. These screws pass through slots 14—14 in the bracket arm and are threaded into the work support 1 and serve as a means to clamp the bracket arm rigidly to 25 the work support, permitting the same to be adjusted in a direction at right angles to the line of feed.
- The stiffening strip guide is indicated at 30 15 and is formed with a guiding recess 16 for the stiffening strip. The stiffening strip goes through this guiding recess unfolded. The guide for the stiffening strip is formed integral with the bracket arm 11^a. Also 35 formed integral with the bracket arm 11^a and the stiffening strip guide is a binding guide 17 which has a guiding recess 18 extending above and below the guiding recess 16 so as to direct a binding strip about the edge of the stiffening strip. The guide for 40 the stiffening strip is extended laterally, as indicated at 19, and mounted on this lateral extension is an edge guide 20 for the body fabric. Said edge guide 20 is formed with a slot 21 through which screws 22—22 pass, and which serve as a means for permitting 45 an adjustment of the guide in a direction at right angles to the line of feed. The guide member for the stiffening strip is formed with a slot 23 through which an implement 50 may be inserted for facilitating the insertion of the stiffening strip in the guide.
- Below the stiffening strip guide is a guide 24 for a tacking strip. This guide 24 is formed with a flat tubular extension for 55 directing the tacking strip without folding either edge thereof. The guide 24 is carried by a depending arm 25 which in turn is carried by a shank 26 having slots 27—27 for screws 28—28, so that this tacking strip 60 guide may be adjusted in a direction at right angles to the line of feed. The work support is recessed, as indicated at 29, so that this tacking guide may be placed below the guiding device for the stiffening strip, which is 65 mounted directly on the work support, and

extend to a point so as to direct the tacking strip underneath the presser foot of the machine, indicated at 30 in the drawings.

In the operation of the machine, the lining strip L is directed through the lining strip 70 guide 8, the edges *l* and *l'* are inturned, and the body fabric B is guided by the edge guide 20, and this edge guide is so positioned as to direct the body fabric to the needle 4. A stiffening strip S is directed to the stiffening strip guiding recess 16, and this is so disposed that the line of stitching N formed by the needle 4 and cooperating looper 6 passes through the infolded edge of the lining strip, the body fabric and the edge of the stiffening strip. At the same time, a binding strip C is led through the binding guide 17, and folded about the edge of the stiffening strip. A tacking strip T is led through the tacking guide 24, and this tacking guide and binding 75 guide are so disposed that the line of stitching N' formed by the needle 5 and cooperating looper 7 passes through the infolded edge of the lining strip, through the binding strip, the stiffening strip and the tacking strip. 80 Thus it is that the waist band parts are practically all completed in one operation. A belt loop may be placed on the body fabric and guided along with the same and stitched between the lining strip and the body fabric 85 by the line of stitching N.

It is obvious that minor changes in the details of construction may be made without departing from the spirit of the invention as set forth in the appended claims.

Having thus described the invention, what I claim as new and desire to secure by Letters-Patent, is:—

1. A sewing machine for stitching waist bands comprising stitching mechanism having spaced needles for forming two rows of stitches, a guide for the lining strip shaped to infold the edges thereof, a guide for the stiffening strip located beneath the lining strip guide, a binder for directing the binding about the edge of the stiffening strip, said binder being disposed in advance of one of said needles, an edge guide disposed in advance of the other needle for directing the edge of a body fabric between the lining strip and the stiffening strip, and a guide located beneath the stiffening strip guide for directing a tacking strip to the needle stitching the binding to the stiffening strip.

2. A sewing machine for stitching waist bands comprising a work support, an overhanging arm, a needle bar mounted in the overhanging arm, two spaced needles carried by the needle bar, a looper beneath the work support for each needle, a lining strip guide carried by the overhanging arm and having means for infolding the edges of the lining strip and directing the same to the needles, a stiffening strip guide mounted on the work support for directing the stiffen- 120

ing strip to the two needles, a binding guide for directing the binding about one edge of the stiffening strip and to one of said needles, said binding guide being carried by 5 the work support, and an edge guide for directing the edge of a body fabric between the lining strip and the stiffening strip and to the other needle, said stiffening strip guide having a lateral projection, and said 10 edge guide being adjustably mounted on said lateral projection.

3. A sewing machine for stitching waist bands comprising a work support, an overhanging arm, a needle bar mounted in the 15 overhanging arm, two spaced needles carried by the needle bar, a looper beneath the work support for each needle, a lining strip guide carried by the overhanging arm and having means for infolding the edges of the

lining strip and directing the same to the 20 needles, a stiffening strip guide mounted on the work support, for directing the stiffening strip to the two needles, a binding guide for directing the binding about one edge of the stiffening strip and to one of said needles, 25 said binding guide being carried by the work support, and an edge guide for directing the edge of a body fabric between the lining strip and the stiffening strip and to the other needle, said work support having a 30 recess therein, and a tacking strip guide located beneath the work support and having its delivering end extending into said recess, and means for supporting said tacking strip guide from the work support. 35

In testimony whereof, I affix my signature.

BENJ. V. KERSHNER.
